UNITED STATES PATENT OFFICE.

LEVI ORSER, OF GALVESTON, TEXAS.

FEEDER FOR POWER PRINTING-PRESSES.

SPECIFICATION forming part of Letters Patent No. 406,058, dated July 2, 1889.

Application filed December 29, 1887. Serial No. 259,294. (Model.)

To all whom it may concern:

Be it known that I, LEVI ORSER, of Galveston, in the county of Galveston and State of Texas, have invented a new and Improved 5 Feeder for Printing-Presses, of which the following is a full, clear, and exact description.

This invention relates to feeders for printing-presses, and has special reference to its employment in power-presses in which the 10 feeder takes up the paper from the feed-board, at the same time turning up its front edge, and carries and deposits it to be seized by the nippers. To accomplish this, lifters are employed which hold the paper by means of a 15 mechanism which produces a partial vacuum, which is destroyed when the lifters have deposited the paper for the nippers.

In the construction of this device holders for holding and transferring the paper, one sheet 20 at a time, are mounted on a horizontal rod, which is raised and lowered vertically by a vertically-reciprocating lever and carried horizontally by a vertically-swinging lever in sleeves which connect said levers, whereby they both 25 swing horizontally. The vertically-swinging lever referred to is mounted on a horizontal rock-shaft at the top of the machine, which is provided with a lever-arm having a retracting-spring. From the horizontal rock-shaft de- 30 pends an arm, to which is secured a sleeve having the horizontally-swinging lever and the vertically-reciprocating lever above mentioned, the former being fixed thereto and the latter adapted to move therein. These levers 35 pass through sleeves, to the upper one of which the horizontally-swinging lever is fastened and through which the vertically-reciprocating lever moves freely, with a retracting-spring on the reciprocating lever located be- 40 tween the sleeves. The reciprocating lever is fastened to the lower sleeve and the horizontally-swinging lever slides therein. The horizontally-swinging lever is operated by a cam to swing it forward on its horizontal shaft, 45 and is thrown back to a vertical position by the spring-actuated arm on its shaft. The vertically-reciprocating lever is actuated by a cam to raise it, and is drawn down, when released from the cam, by means of the retract- 50 ing-spring located between the sleeves above mentioned.

The holders for raising and transferring the paper communicate with a vacuum-pump operated by a lever acted upon by a cam, said lever being provided with a cam-joint which 55 wedges against and tightens a sleeve on the piston-rod of the vacuum-pump and carries down the piston, so as to destroy the vacuum when the paper is deposited. The several cams heretofore mentioned are mounted on 60 the same shaft, driven by any suitable power. The cams are so timed in their construction that a vacuum will be produced to hold the paper while being transferred to the nippers. The holders are raised by the vertically-re- 65 ciprocating lever and swung over to the nippers by the horizontally-swinging lever and deposited by means of the vertically-reciprocating lever. At this point the vacuum is cut off from the holders by the sleeve sliding on 70 the piston-rod, in conjunction with the cam-joint on the pivot-lever before referred to. By the further rotation of the main shaft and its cam the holders are raised and swung back and deposited on the paper on the feed-board, 75 the piston meanwhile having been drawn up to again form a vacuum.

Reference is to be had to the accompanying drawings, forming a part of this specification, in which similar figures of reference indicate 80 corresponding parts in all the views.

Figure 1 is a front view of the feeder, showing the lifters in position to transfer a sheet of paper from the feed-board to the nippers. Fig. 2 is a side view thereof with the frame- 85 work broken away. Fig. 3 is a side view similar to Fig. 2, except that the parts are in position, when the holders have been raised, to transfer a sheet of paper. Fig. 4 is a similar side view showing the holders in position with 90 the paper deposited. Fig. 5 is a detail view of the upper part of the machine, showing the vertical levers broken away and mounted on their horizontal shaft. Fig. 6 is a detail view of the device, with parts broken away, for 95 turning up the edge of the paper. Fig. 7 is a modification in vertical section of one of the lifters with its connecting-tube broken away. Fig. 8 is a detail view showing the vacuum-producing mechanism with the cylinder in 100 vertical section. Fig. 9 is a detail view of the upper portion of the horizontally-swinging le-

ver with the spring-actuated arm for throwing it into a perpendicular position. Fig. 10 is a modification of the spring-actuated arm, showing it attached to the horizontal shaft. 5 Fig. 11 represents, partly in section, a modification of the turner mechanism; and Fig. 12 is a front view thereof with connections broken away.

Referring to the drawings, 1 indicates the 10 frame-work upon which the feeder mechanism is mounted, and 2 the feed-board, having the retaining-plates 3 adjustably mounted thereon by means of nuts and pins 4, resting in slots 5 on the edge of the feed-board. The 15 retaining-plates may be covered with rubber 6 to form a holding-surface for the edges of the sheets. In lieu of the rubber covering, metallic springs may be employed.

The holders for holding the paper when 20 transferred consist of flat suction disks or holders 7, of rubber or other suitable material, connected by flexible tubes 8 with a pipe 9, leading to the cylinder 10 of a vacuum-pump, as shown in Fig. 2. The tubes 8 are flexible, 25 in order to allow for the vertical and horizontal movements of the holders 7. The holders 7 are mounted on a horizontal rod 62 by means of sleeves 63 and set-screws 64, the sleeves 63 having clamping-plates 65, between which the 30 tubes 8 are clamped and fastened by means of set-screws 66. Instead of flexible tubes, rigid tubes might be employed connected to the pipe 9 by a universal joint to permit of the same range of movement. The disks 7 35 are flush with the ends of the tubes, as shown, but are flared up at the center and joined to the tubes 8 a little above the ends. They may be provided with stop-cocks, so that where several holders are in use and it is desired to 40 remove one it can be unfastened and the tube closed.

The vacuum-pump consists of the cylinder 10 and the piston 11, having a cross-head 12, sliding on the standards or rods 13 of the 45 frame-work and bearing against retracting coil-springs 14. The latter may be adjusted as to tension by means of sleeves 15, sliding on the rods 13 and on rods 16, mounted on the cross-piece 18, to which they are secured by 50 set-screws 19. The piston-rod 20 of the piston 11 has mounted thereon a sleeve 21, having a projection 22, which is adapted to be brought against a stop 23. The sleeve 21 is provided with ears 24, in which is pivoted a 55 cam-shaped joint 25, connected by a pin 26, resting in a slot 27, with a lever 28. The cam-shaped joint 25 is provided with a spring 29, suspended from a rod 30. A lever 28 is pivoted at 32 on an arm 33 on the frame-work 1, 60 and carries a friction-roller 34, which is acted upon by a cam 35 to force down the lever 28, carrying with it the cam-shaped joint 25, and wedging the latter against the piston-rod 20, thereby carrying down the piston 11 and destroying the vacuum. Upon the lever 28 being 65 released by the cam 35 the spring 29 draws up the joint 25, thereby releasing the sleeve

21 from the piston-rod 20 and allowing the latter to be drawn up by springs 14, acting on the cross-head 12 and creating the vacuum. 70 The upward movement of the piston is lessened by the loosening of the sleeve on the piston-rod and the removal of the action of its lever. The action of the vacuum-producing mechanism times the movement in creating and destroying the vacuum in accordance with the movement of the lifting and transferring mechanism. The piston 11 should be kept covered with oil. The vacuum-cylinder 10 is provided with a stop-cock 86 to draw off 80 any oil which may work below the piston 11.

At the top of the frame-work 1 is mounted a horizontal rock-shaft 36, from which depends an arm 37, having a sleeve 38 secured thereto by a set-screw 39. 85

40 indicates the horizontally-swinging lever rigidly secured to the sleeve 38 and to a second sleeve 41 by means of a set-screw 42, and having its lower end adapted to slide in the sleeve 43. The lever 40 is provided with 90 a V-shaped slotted portion 44, having a friction-roller 45 mounted therein, which is acted upon by a cam 46 to throw the lever 40 forward, the lever 40 being retracted to a vertical position by an arm 47, mounted on the 95 rock-shaft 36, and a spring 48, connected with the frame-work 1.

49 indicates a lever which reciprocates vertically and swings horizontally. Its upper end is adapted to move in the sleeve 38, and 100 is formed with a bent portion 50, having a slot 51, which engages the pivot-pin 52, carrying a friction-roller 53 on the lever 54, pivoted at 55 to the frame-work 1. The connection by means of the slot 51 and pivot-pin 52 permits of a horizontally-swinging movement of the lever 49. The lever 49 is adapted to move freely through the sleeve 41, and is secured to the sleeve 43 by means of a set-screw 56. It is raised vertically by means of a cam 57, 110 which moves in a slot in the portion 50 and bears against the friction-roller 53 on lever 54, and is drawn down by the retracting-spring 58, mounted on the lever 49, between the sleeves 41 and 43. The cams 46, 55, and 57 are mounted on the shaft 59, which is driven by any suitable power.

For the sake of illustration, shaft 59 is shown as provided with a train of gearing 60, operated by a crank 61. The sleeves 38, 41, and 43 connect the levers 40 and 49, so that they will swing horizontally together and also permit the lever 49 to raise and lower the sleeve 43, and with it the turner mechanism, which will now be described.

In transferring a sheet of paper it is desirable to present the upturned edge of the sheet to the nippers. For this purpose, the suction-disks or holders 7, which are secured to the horizontal rod 62, are provided with a mechanism to tilt them slightly and lift up the edge of the paper. The rod 62 is provided with a lever 67, pivoted at 68 to a foot-piece 69, and at its other end is connected, by means

of a slot 70 and pin 71, with a vertical piece 72, having a rod 73, which is secured in the sleeve 74 by a set-screw 75. An arm 76 passes through the sleeve 74, and is bent outward 5 and downward and fastened to the foot-piece 69. Rod 73 and arm 76 pass through a sleeve 77, the arm 76 being secured thereto by set-screws 78.

The operation of the turner device is as follows: The sleeve 43, when lifted by the lever 49, carries with it the sleeve 74 and raises the forward end of the lever 67. The foot-piece 69 presses against the feed-board and thereby 10 tilts the disks or holders 7 and raises up the edge of the paper. The turner movement is limited by means of the sleeve 74 abutting against the sleeve 77. The range of movement of the turner mechanism may be adjusted by means of a sleeve 80, which is adjustable on the rod 73 by means of a set-screw 81, as shown in Figs. 4 and 6. The turner mechanism carrying the holders is secured to the transferring-levers by an arm 79 on the sleeve 74, which passes through sleeve 43 and 15 is held therein by a set-screw. (Not shown.)

The operation of my device is as follows: A pile of sheets having been placed on the feed-board 2, the holders 7 are brought into contact with the top sheet, as shown in Fig. 2, by the revolution of the shaft 59 and the rotation of the cams 46 and 57 from the position shown in Fig. 4. The cam 57 raises the lever 49 and its connecting parts, carrying the holders, and the cam 46, swinging lever 40, lever 49, and connecting parts with the holders over the feed-board 2, where the cam 57 permits the spring 58 to force the lever 49 and its connecting parts down, thereby bringing the holders 7 against the paper. In the 20 position of the parts as shown in Fig. 4 the short arm of the cam 35 has forced down the lever 28, and by means of the cam-joint 25 engaging the piston-rod 20 the piston has been forced down, the vacuum destroyed, and 25 the sheet of paper released. During the revolution of the shaft 59 and cams 57 and 46, as above described, the long arm of the cam 35 is released from the lever 28, and the tension of the spring 29 releases the cam-face 31 from 30 the sleeve 21 and draws up the latter on the rod 20 until its projection 22 abuts against the stop 23. The piston 11 is then drawn up by the reaction of the compressed springs 14, and a vacuum is formed to retain the sheet 35 against the holders 7 when in position, as in Fig. 2. Upon the further revolution of the shaft 59 the cam 57 is brought to the position shown in Fig. 3, thereby lifting the lever 49 and the holders 7, carrying a sheet of paper, 40 and upon the further revolution of the shaft 59 the spring 48 swings the lever 40 and lever 49 and their connections with the holders over to the nippers, (not shown,) and upon the release of the cam 57 from the lever 49 the latter is forced down by the spring 58, carrying 45 with it the holders and paper sheet. The vacuum mechanism has during this latter op-

eration operated as described above and the paper is released. The action of the turner mechanism at the beginning of the foregoing 70 operation has been described above.

In lieu of the arm 47 and its spring 48, I may employ an adjustable tension device, as shown in Fig. 10, which consists of a spring 82, secured at one end to the rock-shaft 36 and 75 coiled about it, and secured at its other end to a lug 83 on a sleeve 84 by being bent around it and over the sleeve 84, held on the rock-shaft 36 by a set-screw 85. The spring 82 may be tightened on the rock-shaft 36 by 80 turning the sleeve 84 thereon and securing it by a set-screw 85.

In Fig. 7 I have shown a modification of the paper-holding disk, whereby a firm hold of the paper is secured. In this construction the 85 center of the flexible disk 87 is made concave and the end 88 of tube 8 projects therein.

In order to lift a sheet of paper from a pile, it is necessary to lift one side first, in order to allow the air to pass between it and the next 90 sheet, and it is manifest that the end of a tube, even though cushioned, could not accommodate itself to the inclined sheet or to a bent or rumpled sheet, and an aperture or opening would be left between one side of the 95 sheet and the tube, through which the air would rush and prevent a vacuum. The air would pass into the holder-tube between its lower end and the upper face of the sheet, and therefore atmospheric pressure could not 100 be exerted against the lower side of the sheet to press it against the tube; but I provide a thin flexible disk 87, as above stated, so that when the tube descends the disk will accommodate itself, by reason of its elasticity, to the 105 position or bend of the sheet, and as soon as the air is exhausted from the tube, or suction begins, the atmospheric pressure on the upper side of the disk will press the edges of the disk down at all points, and the holder cannot 110 fail to operate. By having the disk concaved on its under side the outer edges will first engage the paper, and an air-tight joint will be more quickly formed, and as the tube projects into the concavity the yielding of the 115 disk will cause the sheet to be evenly presented to it, and no air openings or spaces can be formed between it and the sheet. I am aware that a pneumatic paper-holding tube has had its lower end cushioned by an elastic 120 band, and I claim no such construction, for this band could in no way be affected by the atmospheric pressure, and could not form an elastic disk designed for or capable of the same operation as mine.

In the modification shown in Figs. 11 and 12 the turner consists of a horizontal vibrating lever 89, pivoted to a vertical rod 90, secured in sleeve or block 43 by set-screw 56. The forward end of vibrating lever 89 has 130 secured therein the rod 62, which supports paper-holding disks 7, and is provided at its rear end with friction-rollers 91, which may be covered with some soft material to avoid

marring the paper. The lever 89 also has a rod 92 on its rear end, on which one or more counterpoise-weights 93 may be placed, serving as a foot piece or rest. A sleeve or block 94, with projection 95, is secured to rod 90 by set-screws 96, and serves as a stop to limit upward movement of lever 89 and lifters 7. When the lever 49 is raised, it carries with it rod 90, and raises the forward end of lever 89 10 and lifters 7 until stopped by projection 95. The rear end of lever 89 is held down by counter-weight 93, and the turner is drawn along by the swing of the transferring mechanism, with the lever 89 resting on rollers 91.

15 I lay no claim herein, broadly, to pneumatic holders raised and lowered and moved horizontally with a vacuum-producing device, for such I have already claimed in an application pending herewith.

20 Having thus fully described my invention, what I claim as new, and desire to secure by Letters Patent, is—

1. In a feeding mechanism for power printing-presses, the combination, with a rod or 25 support carrying the paper-holders, of a combined mechanism for raising the holder rod or support, swinging it horizontally, and lowering it, consisting of a horizontally-swinging lever suspended from a rock-shaft, and a reciprocating lever sliding in coupling-sleeves 30 secured to the horizontally-swinging lever, cams for operating said levers in one direction, and reacting springs for moving them in the opposite direction, substantially as described.

35 2. The combination, with the pneumatic paper-holding tube, of a thin flexible disk on the lower end thereof to establish an airtight connection between the tube and sheet 40 by atmospheric pressure on its upper side when the suction in the tube begins, substantially as set forth.

45 3. A suction paper-holding disk for printing-presses, consisting of a disk of flexible material, concave in the center and flat at the edges, and having its connecting-tube projecting therein, substantially as described.

50 4. In a feeding-machine for power printing-presses, a mechanism for raising and lowering the paper-holders, consisting of a vertically-reciprocating lever connected to a pivoted lever by a sliding-pin connection, a cam moving in a slot and bearing against a friction-roller in the reciprocating lever to move it in 55 one direction, and a retracting-spring, substantially as described.

55 5. In a feeding mechanism for power printing-presses, a mechanism for swinging the paper-holders horizontally and moving them 60 vertically, consisting of a horizontally-swinging vertical lever, a rock-shaft having bearings in which said lever slides, a cam for moving said lever in one direction, and a reacting spring actuating the rock-shaft, substantially as described.

65 6. In a feeding mechanism for power printing-presses, a mechanism for swinging the

paper-holders horizontally, consisting of a horizontally-swinging vertical lever suspended from a rock-shaft having an adjustable 70 reacting spring, and a cam acting on a friction-roller in a slot in said horizontally-swinging lever, substantially as described.

7. In a feeding-machine for power printing-presses, the combination, with pneumatic 75 holders, of a vacuum-producing mechanism consisting of a vacuum-pump, a cam, a lever forced down thereby and having a cam-joint connecting it with a sliding sleeve on the piston-rod, said cam-joint engaging the piston-rod when its lever is forced down, and reacting springs to raise the piston-rod, and a mechanism for raising and lowering the holders, consisting of a horizontally-swinging lever suspended from a rock-shaft, and a vertically-80 reciprocating lever sliding in sleeves coupling the levers together, cams for operating the levers in one direction, and reacting springs 85 for moving them in the opposite direction, substantially as described.

90 8. In a feeding-machine for printing-presses, a turner mechanism for turning up the paper-holding disks, consisting of a frame provided with a horizontally-vibrating lever having a foot-piece and a rod carrying the paper-holding disks, and a stop on the frame to limit the upward movement of the forward end of the vibrating lever, substantially as described.

95 9. In a feeding-machine for printing-presses, a vacuum-producing device, consisting of a vacuum-pump, a cam, a lever having a cam-joint to engage the piston-rod and provided with reacting spring, and a sliding sleeve on the piston-rod and to which the said joint is connected, a projection on said sleeve adapted 100 to strike against a stop, and reacting springs 105 to raise the piston, substantially as described.

110 10. In a feeding-machine for power printing-presses, the combination, with a vertically-reciprocating lever operated by a cam and reacting spring, of a device for turning up the paper holders or disks, consisting of a vertical rod secured in a sleeve on the vertical reciprocating lever and moving in a sleeve secured to a bent arm pivoted to a foot-piece 115 having a pivoted lever in which the holder-rod is mounted, and connected by a slotted joint with the vertical rod, substantially as described.

115 11. In a feeding-machine for power printing-presses, the combination, with a vertically-reciprocating lever operated by a cam and reacting spring, of a mechanism, substantially 120 as described, for turning up the paper-holders, substantially as described.

125 12. In a feeding-machine for power printing-presses, a turner mechanism consisting of rod 62, lever 67, foot-piece 69, arm 76, sleeves 74 77, set-screws 75 78, rod 73, adjusting-sleeve 80, set-screw 81, and arm or rod 79, 130 substantially as described.

13. In a feeding-machine for printing-presses, the combination, with suction-disks having freely-movable connecting-tubes and

- mounted on horizontally-swinging vertical levers, one of which reciprocates in sleeves coupling the levers together, of a vacuum-pump, a cam, a lever connected with a sliding sleeve on the piston-rod by a cam-joint to engage the piston-rod, and having a reacting and releasing spring for raising the piston, and a stop for limiting the upward movement of the sleeve, substantially as described.
- 10 14. In a feeding - machine for printing-presses, a vacuum-producing and cut-off device consisting of cam 35, lever 28, operated thereby, cam-joint 25, spring 29, sleeve 21, to which the said joint is pivoted, projection 22 on the sleeve, stop 23, piston-rod 20, operated by the cam-joint and on which the sleeve slides, and piston 11, cylinder 10, cross-head 12, rods 13, and springs 14, substantially as described.
- 15 15. In a feeding - machine for printing-presses, a horizontally-swinging vertical lever suspended from a rock-shaft provided with a reacting spring adjustable thereon as to ten-
- sion by means of a sleeve and set-screw, said swinging lever being actuated by a cam, substantially as described.
16. In a feeding-machine for power printing-presses, the combination of the shaft 59, driven by suitable power and having cams 35, 46, and 57, rock-shaft 36, having reacting 30 spring, and arm 37, with sleeve 38, lever 40, secured to sleeves 38 and 41 and sliding in sleeve 43, lever 49, having a slotted connection with lever 54 and sliding in sleeves 38 35 41, and secured to the sleeve 43, and provided with a reacting spring 58, with a turner mechanism consisting of a rod secured in sleeve 43, carrying a sleeve, and a system of rods and levers, substantially as described, with a foot-piece, all connected to the paper-holder 40 rod, as shown and described.
